UNITED STATES PATENT OFFICE

2,665,012

WIRE LIFTING CRANE

Ray McLain and Theodore A. Fornkah, Cape Girardeau, Mo.

Application January 22, 1949, Serial No. 72,122

1 Claim. (Cl. 212—8)

1

This invention relates to a wire lifting crane for use on power distribution poles. More specifically it relates to a crane of the kind described having a boom which is pivoted for motion in a vertical plane.

An object of the invention is to provide a crane which can be mounted either at the top of a pole or on a cross-arm.

Another object of the invention is to provide a crane having a boom pivoted for limited pivotal motion in a vertical plane.

Still another object of the invention is to provide a crane having a boom which is rotatable about a vertical axis so that it can be utilized with either of two sets of positioning notches.

Yet another object is to provide a crane which is simple yet rugged.

A further object is to provide a crane which can be tilted from a position in which the wire being lifted will clear the pole to one in which the wire lifted will be positioned over the insulator to which it is to be fastened.

Yet a further object of the invention is to provide suitable means for supporting the crane on a pole.

These and other objects will become apparent from a study of this specification and the drawings which are attached hereto and made a part hereof and in which:

Figure 1 is a side elevation of the crane mounted on a cross-arm.

Figure 2 is an end elevation of the apparatus of Figure 1 viewed from the left thereof.

Figure 3 is a view partly in section showing the lower portion of the boom.

Figure 4 is a side elevation of the crane mounted at the top of a pole.

Figure 5 is an end elevation of the crane showing a modified form of cross arm mounting means.

Referring now to Figures 1 to 3, the numeral 1 refers to a cross-arm having an insulator 3 mounted thereon.

The crane comprises a channel shaped base 5 which is open downwardly and is proportioned so as to fit the top edge of a cross-arm. A pair of hooks 7 extend laterally from the top of the base to support the chains 9 and 11 which are connected by a toggle clamp mechanism 13 of conventional construction.

Fixed to the upper face of the base are a pair of parallel, spaced sector plates 15 which are spanned by a back plate 17. Each sector has spaced notches 19 and 21. The corresponding notches in the plates are aligned.

2

A pivot pin 25 is fixed in the sectors and a bearing or support member 27 is pivoted on the pin. The member has two guide portions 29, 31 which are separated by a groove 33.

The boom 35 is preferably a tube formed with a downwardly curved upper end 37 which terminates in an eye 39 which receives a pulley block 41.

The lower end of the tube is notched at 43 to receive the pin 25 and slidably receives the guide portions 29, 31. A pair of pins 45 are fixed in the tube and extend radially into the groove 33. When the notches 43 rest on the pin 25, the pins 45 rest at the bottom of the groove. This permits the boom to be lifted far enough to disengage the notches and pin.

A rope or other line 47 is supported in the block and a hook 49 may be fastened to one end thereof to lift the power wire 51.

Another pin 53 is fixed in the boom above the pins 45 and extends from each side of the tube. The pin is positioned so that it is seated in the notches 19 when the lower notches 43 engage pin 25.

Operation

The crane is mounted with the base 5 spanning the upper side of the cross-arm 1 and suitable links of the chains 9 and 11 are engaged with hooks 7 and with the toggle clamp 13. When the clamp is closed, the chain is tightened so as to hold the base firmly on the arm.

With the boom in the position shown in Figure 1, the hook 49 is lowered to the ground and engaged with a wire. The wire is then lifted until it is slightly higher than the insulator 3. The boom of the crane is then swung toward the dotted line position (Figure 1) until the wire is directly over the insulator upon which it is then lowered.

The pin 53 engages the ends of the notches 19 to limit the pivotal movement of the boom.

When it is desired to use the crane to mount a wire on an insulator 55 which is supported on top of a pole 57, the base is clamped to the side of the pole by means of chains 9, 11 and toggle clamp 13. Thereafter the boom is slid outwardly on the support guides, away from pin 25. This disconnects notches 43 from pin 25 and pin 53 from notches 19.

The boom (Figure 4) is then rotated 180 degrees on guides 29, 31 and rotated about pin 25 until pin 53 is adjacent notches 21. The boom is then slid toward pin 25 to reengage it with notches 43 and pin 53 with notches 21.

Operation of the device in this position is similar to that previously described.

Modified clamp

(Figure 5)

Instead of using the chain to clamp the crane on a cross-arm I may turn up the lower edges of the base to form channels 59. A U-shaped clamp 61 has hooks 63 formed at the ends thereof to enter and interlock with the channels.

A threaded hub 65 is fixed to the center portion of the clamp and a hand screw 67 is mounted therein.

The application of the clamp is obvious.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claim.

What I consider to be new and desire to protect by Letters Patent of the United States is:

In a crane, the combination of a base, clamping means for detachably mounting said base on a supporting means, a support member having axially aligned and axially spaced cylindrical guide portions, a tubular boom having a longitudinal axis, said boom having one end mounted on said guide portions for rotation and for axial translation thereon to and from a normal position, means on said boom extending into the space between said guide portions for engaging them to limit the axial translation of the boom, a pivot pin engaging said base and support member and cooperating therewith to mount said boom for movement through an arc in a plane which intersects said base, means defining diametrically opposed, axially directed notches in the end of the boom, said notches and pivot pin being engaged

when said boom occupies its normal axial position and serving to hold the boom in one or the other of two rotated positions, the other end of said boom being offset from said axis, a pulley, means for mounting said pulley on said other end of the boom, stop engaging means mounted on said boom, said stop engaging means being moved in a predetermined path as said boom moves through its arc while occupying said normal axial position and being moved out of said path when said boom is displaced from said normal axial position, and a series of stop means mounted on said base and disposed at spaced points along the path of and for engagement with said stop engaging means, said stop means and stop engaging means serving to limit the pivotal motion of said boom to any selected one of a number of segments of its pivotal arc.
